Des. 211,799
Patented July 30, 1968

211,799

CONSOLE FOR AN AUTOMATIC BOWLING SCORING SYSTEM OR SIMILAR ARTICLE

Daniel D. Miller, Sunnyvale, Calif., assignor to
Doban Labs, Inc., Sunnyvale, Calif., a corporation of California

Filed Oct. 9, 1967, Ser. No. 8,904

Term of patent 14 years

(Cl. D34—5)

Fig. 1

Fig. 2

Fig. 3

Fig. 4

FIG. 1 is a perspective view, taken from the front and slightly above and to the right of center, of a console for an automatic bowling scoring system or similar article showing my new design;

FIG. 2 is a front view of the console of FIG. 1;

FIG. 3 is a left side view of the console of FIG. 1, the right side view being substantially the same; and

FIG. 4 is a rear view of the console of FIG. 1.

I claim:

The ornamental design for a console for an automatic bowling scoring system or similar article, substantially as shown and described.
